UNITED STATES PATENT OFFICE.

SAMUEL TRETHEWEY, OF PITTSBURG, PENNSYLVANIA.

PISTON.

SPECIFICATION forming part of Letters Patent No. 693,085, dated February 11, 1902.

Application filed February 7, 1901. Serial No. 46,309. (No model.)

To all whom it may concern:

Be it known that I, SAMUEL TRETHEWEY, a citizen of the United States of America; and a resident of the city of Pittsburg, county of Allegheny, Commonwealth of Pennsylvania, have invented certain new and useful Improvements in Pistons, of which the following is a specification.

Referring to the drawings which make part of this specification, Figure I is an elevation of my improved piston, partially cut away to show parts. Fig. II is a plan view of the same with the front plate removed. Fig. III shows my improved set ring. Fig. IV is a sectional view of the same along the line a a in Fig. III; and Fig. V is a sectional detail view of my packing-rings, showing the same connected by lip and recess.

Generally stated, my invention consists in an improved piston so constructed that the packing or bearing surface can easily be adjusted to take up wear and at all times to snugly fit the bore of the cylinder. The arrangement of back and front plates is such that under no circumstances can the wearing away of the bearing-surface allow said plates to come into contact with the cylinder-bore.

My invention is applicable in all cases where a piston traversing the interior of a cylinder is utilized, and in case the stroke is very short, as in a valve, I provide the bearing-surface with projections or tongues at its front and rear edges, thus giving the piston a longer bearing-surface and preventing the excessive friction usually attendant upon the use of a narrow piston.

The following is a detailed description of my invention, reference being had to the drawings.

1 is the piston-rod. 2 is a collar fixed thereon.

3 is the back plate of the piston, which is slipped down over the piston-rod 1 and bears against collar 2.

4 is the front plate, also fitted to slip over piston-rod 1.

5 is a split set-ring, preferably made of spring-steel, intended to be seated in the annular recess formed by the offsets 6 6^a in plates 3 and 4 when said plates are in position, as in Fig. I.

7 7^a are split bearing-rings or packing, constructed in the form of two rings with their adjacent surfaces adapted to fit snugly together and their opposite edges indented to form a series of projections 8 8, the use of which projections is hereinafter described, said opposite edges of said bearing-rings extending over the edges of the back and front 60 plates of the piston and being between the same and the bore of the cylinder, as shown in Fig. I.

9 9^a are annular flanges on rings 7 7^a and are seated in the recess formed by the offsets 6 6^a in plates 3 and 4.

Projections 8 8 on ring 7 7^a are for use in cylinders where the stroke is short and the width of the piston is required to be slight, such as when the orifices of a valve are to be alternately opened and closed. In such cases the friction of the piston upon the bore of the cylinder is very great and undue wear results. By means of these projections or tongues 8 8 I procure a much larger bearing-surface for 75 the piston, thus steadyng the piston and reducing the friction, while the indentations between the projections being preferably of a greater area than the projections prevent undue closing of the valve-orifices and cause 80 such orifices to be exposed in as satisfactory manner as if the entire bearing-surface of the piston were as narrow as my piston between two opposite indentations.

10 is an annular lip (not shown in Fig. I) 85 on one of the split packing-rings, as 7, which lip registers when the members of the piston are assembled with recess 10^a in the other packing-ring, as 7^a. By means of this arrangement the packing-rings are kept in the 90 same relative position and present a regular and smooth surface to the bore of the cylinder. This arrangement of lip and recess also prevents the steam from expanding the packing-ring, against which it is directly exerted 95 in a greater degree than the other packing-ring, in which case an irregular packing-surface would be presented to the cylinder-bore and "barreling" of a cylinder near its ends would result.

The method of assembling my improved piston is as follows: First, plate 3 is slipped down over the end of the piston-rod until it rests against collar 2. The set-ring 5 is then

seated in annular offset 6 in plate 3. The bearing-ring 7 is then rested on offset 6, and upon it is placed bearing-ring 7^a. The action of set-ring 5, which is made the same width as the flanges 9 and 9^a together, tends to expand the split bearing-rings 7 7^a, thus enabling them to maintain a snug fit with the cylinder-bore. The rings 7 7^a are assembled so that their split portions do not register, thus preventing the formation of an orifice or leak through the piston, the bearing-rings being held in a fixed relative position by pin 10 passing through both rings. After the above parts are in place front plate 4 is slipped on, and nut 11 is screwed on the end of piston-rod 1 until the plate 4 is forced snugly against plate 3. The width of set-ring 5 or the combined width of flanges 9 and 9^a is slightly less than the width of offsets 6 6^a, thus leaving set-ring 5 free to expand the bearing-rings 7 7^a and keep the same snugly fitting the bore of the cylinder.

I form my set ring preferably of spring-steel, and its inner edges are cut into annular offsets or recesses 12 12, producing the cross-sectional form shown in Fig. IV, and the thickness of cross-section of said set ring tapers toward the split ends to increase its spring force. By using this cross-section I find that in case it is desired to spread set-ring 5 it can be readily taken out and hammered along its inner surface opposite to the split, thus causing the split to open wider and the ring to expand. Owing to the form of cross-section I use this hammering does not displace the metal of the ring or distort the same, so destroying its fit in the piston, but simply expands the ring in a symmetrical manner. It will thus be seen that in case wear causes my piston to become loose in the bore of the cylinder, so that the expansive force of set-ring 5 no longer keeps the bearing-rings 7 7^a snugly against the bore of the cylinder, it is only necessary to remove the set-ring, expand it by the above described method, and replace it again in the piston, whereupon it will expand the split bearing-rings when the parts are reassembled, causing said bearing-rings to again fit snugly in the bore of the cylinder.

It will readily be seen from the above that my invention is a great advance over the prior art for the following reasons *inter alia*: My arrangement of split bearing-rings enables me to at all times maintain a snug fit between the piston and the bore of the cylinder, wear being easily taken up by the expanding force of set-ring 5, this set-ring itself being easily expanded to increase its spring force when the wear has become too great to be taken up by it in its original condition. Again, there is no possibility in my device of the front and back plates of the cylinder-head coming in contact with the bore of the cylinder, as is often the case in the prior art, thus enabling the immediate bearing-surfaces to be made of different metal, such as brass, than the body

of the piston. Again, my form of bearing-surface with indented edges enables me to produce a piston of very narrow width, but capable of doing its work with but little friction, thus making it of great value for use in valves where the piston is of necessity very narrow and the consequent friction between piston and cylinder very great. The arrangement of lip and recess by which the two split packing-rings are held in the same relative position enables the two packing-rings to expand equally when acted upon by the spring set-ring and also does away with the tendency on the part of the steam to expand the packing-ring adjacent to it unduly, so that an irregular packing-surface results, which in turn causes an irregular wear not only upon the packing, but also the cylinder, which becomes eventually barreled at its extremities. This has always been a cardinal objection to that class of pistons wherein the steam is used to expand the packing, and my aim has been to prevent such expansion caused by the steam and to substitute therefor expansion caused by the spring set-ring. The extreme simplicity of my device, consisting of but a few parts solidly constructed, is a great improvement over the other forms of pistons previously used, my invention being cheap in construction, durable in wear, and easily adjustable when in use.

Although I have described my invention minutely, I do not wish to be limited thereby, but claim broadly—

1. In pistons; the combination of front and back plates; an annular packing, and an eccentric spring set-ring bearing against the entire inner surface of said packing.
2. In pistons; the combination of front and back plates; an annular packing consisting of two split rings of L-shaped cross-section, and a split set-ring bearing against the entire inner surface of said packing-ring.
3. In pistons; the combination of front and back plates; an annular packing, and a split spring set-ring bearing against the entire inner surface of said packing and having at its inner edges annular recesses, substantially as and for the purpose set forth.
4. In pistons; the combination of front and back plates; an annular packing having its front and rear edges indented, and a split spring set-ring adapted to bear against the entire inner surface of said packing.
5. In pistons; the combination of front and back plates; an annular packing consisting of two split rings having their outer edges indented, and a split set-ring adapted to bear against the entire inner surface of said packing.
6. In pistons; the combination of front and back plates; an annular packing having its front and rear edges indented, and a split spring set-ring adapted to bear against the entire inner surface of said packing and having at its inner edges annular recesses, substantially as and for the purpose set forth.

7. In pistons; the combination of front and back plates; a packing consisting of two set-rings; an annular recess in one of said rings; an annular lip on the other of said rings adapted to register with said recess, and a split spring set-ring adapted to bear against the entire inner surface of said packing.

Signed by me at Pittsburg, Pennsylvania, this 3d day of January, 1901.

SAMUEL TRETHEWEY.
